CLAIM

The ornamental design for a connector, as shown and described.

DESCRIPTION

This application is a continuation of U.S. patent application Ser. No. 15/442,011 filed on Feb. 24, 2017.

FIG. 1 is a first perspective view of a connector showing our new design;

FIG. 2 is a second perspective view thereof;

FIG. 3 is a first side view thereof;

FIG. 4 is a second side view thereof;

FIG. 5 is a first end view thereof;

FIG. 6 is a second end view thereof; and,

FIG. 7 is a cross-sectional view of section 7-7 of FIG. 4.

The dashed broken lines illustrate portions of the connector that form no part of the claimed design.

1 Claim, 4 Drawing Sheets
